LIGHTING SYSTEM, CONTROL DEVICE
AND CONTROL METHOD

BACKGROUND OF THE INVENTION

1. Field of the Invention

This present invention relates to a lighting system, control device and control method, and more particularly, to a lighting system, control device and control method capable of improving the lighting precision of a light emitting diode.

2. Description of the Prior Art

In the prior art, a light emitting diode is controlled by a microcontroller and driven by a driving current generated by the microcontroller to emit light. The functionality of the microcontroller utilized for controlling the light emitting diode is simple, which may only turn the light emitting diode on or off, or adjust a lighting brightness of the light emitting diode by two levels. Under such a circumstance, the prior art adjusts the lighting brightness of the light emitting diode by replacing resistors with different resistances, in order to adjust the current flow delivered to the light emitting diode. In other words, the conventional control method may not instantly or dynamically adjust the brightness of the light emitting diode.

Therefore, how to improve the control method of the light emitting diode is a significant objective in the field.

SUMMARY OF THE INVENTION

Therefore, the primary objective of the present invention is to provide a lighting system, control device and control method capable of improving the lighting precision of the light emitting diode.

The present invention discloses a control device, for a light emitting diode (LED), wherein the LED is driven by a current to emit light, the control device comprising a microcontroller, coupled to the LED, for providing the current to the LED according to a current setup signal; and a pulse width modulation (PWM) circuit, coupled to the microcontroller, for generating the current setup signal, and adjusting a pulse width of the current setup signal according to a control signal, to adjust the current generated by the microcontroller.

The present invention discloses a control method, for controlling a microcontroller to control a light emitting diode, the control method comprising adjusting a pulse width of a current setup signal delivered to the microcontroller according to a control signal; and providing, by the microcontroller, a current to the LED and adjusting the current according to the current setup signal, to adjust a brightness of the LED.

The present invention further discloses lighting system, comprising a light emitting diode (LED), driven by a current to emit light; and a control device, comprising a microcontroller, coupled to the LED, for providing the current to the LED according to a current setup signal; and a pulse width modulation (PWM) circuit, coupled to the microcontroller, for generating the current setup signal, and adjusting a pulse width of the current setup signal according to a control signal, to adjust the current generated by the microcontroller.

These and other objectives of the present invention will no doubt become obvious to those of ordinary skill in the art

2

after reading the following detailed description of the preferred embodiment that is illustrated in the various figures and drawings.

5 BRIEF DESCRIPTION OF THE DRAWINGS

FIG. 1 is a schematic diagram of a lighting system according to an embodiment of the present invention.

10 FIG. 2 is a schematic diagram of a process according to an embodiment of the present invention.

FIG. 3A illustrates a schematic diagram of a relationship between the control signal, the current setup signal and the average current value of the current setup signal I_{set} according to an embodiment of the present invention.

15 FIG. 3B illustrates a schematic diagram of a relationship between the control signal, the current setup signal and the average current value of the current setup signal I_{set} according to an embodiment of the present invention.

20 FIG. 4 is a schematic diagram of another lighting system according to an embodiment of the present invention.

DETAILED DESCRIPTION

Please refer to FIG. 1, which is a schematic diagram of a 25 lighting system 1 according to an embodiment of the present invention. The lighting system 1 includes a light emitting diode LED and a control device CTRL. The control device CTRL is utilized for controlling operations of the light emitting diode LED, and includes a microcontroller 10 and a pulse width modulation (PWM) circuit 12. The microcontroller 10 is utilized for providing a current I_1 to the light emitting diode LED for lighting. Notably, the current I_1 generated from the microcontroller 10 to the light emitting diode LED may not be precisely adjusted, wherein the 30 current I_1 may only be turned on or off, or adjust the brightness of the light emitting diode LED by two levels. Therefore, the PWM circuit 12 of the present invention adjusts a current setup signal I_{set} delivered to the microcontroller 10 according to a control signal C_1 , for further 35 adjusting the current I_1 outputted from the microcontroller 10 to the light emitting diode LED. The lighting system 1 may be applied to different electronic systems; for instance, the lighting system 1 may be a warning module inside an electronic system, for providing information related to the electronic system to a user. In addition, the lighting system 1 may be applied to a monitor, and the lighting system 1 may receive the corresponding control signal C_1 generated by the monitor, such that the light emitting diode LED may glow according to a preset program or an instruction from the user, to display images on the monitor. The lighting system 1 mentioned above may be modified according to different 40 applications and design concepts, and the present invention is not limited thereto.

The operations of the lighting system 1 may be summarized as a control process 20, as shown in FIG. 2. The control process 20 includes the following steps:

Step 200: Start.

Step 202: The microcontroller 10 provides the current I_1 to the light emitting diode LED according to the current setup signal I_{set} .

Step 204: The PWM circuit 12 adjusts a pulse width of the current setup signal I_{set} delivered to the microcontroller 10 according to the control signal C_1 , to adjust the current I_1 generated by the microcontroller 10.

Step 206: End.

In the embodiment, the PWM circuit 12 is connected to the microcontroller 10 at a current setup pin P_{Iset} . The

microcontroller **10** may be an LED driver, for setting the current I_{11} delivered to the light emitting diode LED according to a current received at the current setup pin P_{-Iset} . In Step **202**, the microcontroller **10** generates the corresponding current I_{11} to the light emitting diode LED according to an average current value of the received current setup signal $Iset$, allowing the lighting system **1** to glow.

In Step **204**, the PWM circuit **12** may adjust a pulse width of the current setup signal $Iset$ delivered to the microcontroller **10** according to the control signal **C1**. As such, the pulse width of the current setup signal $Iset$ may be modulated through instructions generated by the control signal **C1**, which also changes the average current value of the current setup signal $Iset$. Under such a circumstance, the microcontroller **10** may receive the current setup signal $Iset$ with different average current values according to different pulse widths modulated by the PWM circuit **12**. The brightness of the light emitting diode LED may be precisely adjusted by the PWM circuit **12** and the microcontroller **10**. Notably, the control signal **C1** may be generated by the electronic system according to a default program code, such that the light emitting diode LED may glow according to a default sequence. Alternatively, the control signal **C1** may be generated by the electronic system instantly corresponding to different circumstances, such that the light emitting diode LED may instantly adjust its brightness according to different circumstances. Moreover, the control signal **C1** may be generated by the user through an input device, such that the light emitting diode LED may glow according to requirements of the user. As long as the control signal **C1** may instruct the PWM circuit **12** for pulse width modulation, to further adjust the current I_{11} generated by the microcontroller **10** to the light emitting diode LED, the control signal **C1** are within the scope of the present invention.

In brief, the lighting system **1** of the present invention may improve the control method of the light emitting diode LED. Through controlling the microcontroller **10** by the PWM circuit **12**, the precision of the current I_{11} driving the light emitting diode LED may be improved. In another aspect, the present invention utilizes the PWM circuit **12** for providing the current setup signal $Iset$ to the microcontroller **10**, to adjust the brightness of the light emitting diode LED, such that the lighting system **1** may instantly and dynamically adjust the brightness of the light emitting diode LED. Therefore, the lighting system **1** of the present invention may extend functionalities of the microcontroller **10** for controlling the light emitting diode LED, which elevates product quality and meets user requirements.

Then, please refer to FIGS. **3A**, **3B**. FIGS. **3A**, **3B** illustrate relationships between the control signal **C1**, the current setup signal $Iset$ and the average current value of the current setup signal $Iset$ of the lighting system **1**. Lines **300**, **302** respectively illustrate the control signals **C1** at different voltage levels; lines **304**, **306** respectively illustrate the current setup signals $Iset$ corresponding to the lines **300-302**; lines **308**, **310** respectively illustrate the average current value of the current setup signals $Iset$ corresponding to the lines **304-306**. As shown in FIGS. **3A**, **3B**, the control signal **C1** at a high voltage level is illustrated by the line **300**, and thus, a higher pulse width ratio of the current setup signal $Iset$ in one duty cycle is illustrated by the line **304**, such that the higher average current value of the current setup signal $Iset$ is illustrated by the line **308**. The control signal **C1** at a low voltage level is illustrated by the line **302**, and thus, the higher pulse width ratio of the current setup signal $Iset$ in one duty cycle is illustrated by the line **306**, such that the lower average current value of the current setup signal $Iset$

is illustrated by the line **310**. As such, the PWM circuit **12** may precisely generate the current setup signal $Iset$ with different pulse width modulations according to the control signal **C1**. Notably, the control signal **C1** is not limited to instruct the PWM circuit **12** for generating the current setup signal $Iset$ through the signals represented in voltage levels, as long as a signal format of the control signal **C1** may be identified by the PWM circuit **12**, to generate the corresponding current setup signal $Iset$. For instance, the control signal **C1** may instruct the PWM circuit **12** through the signals represented in current levels, frequency modulations, etc., which are also within the scope of the present invention.

Notably, although the PWM circuit **12** instructs the microcontroller **10** through the current of the current setup signal $Iset$ for adjusting the current I_{11} delivered from the microcontroller **10** to the light emitting diode LED, the PWM circuit **12** may also instruct the microcontroller **10** through the voltage of the current setup signal $Iset$ for adjusting the current I_{11} delivered from the microcontroller **10** to the light emitting diode LED. In detail, please refer to FIG. **4**, which is a schematic diagram of a lighting system **4** according to an embodiment of the present invention. The lighting system **4** is similar to the lighting system **1**, and thus, the same components are denoted by the same symbols. Under such a circumstance that the PWM circuit **12** instructs the microcontroller **10** through the voltage of the current setup signal $Iset$, the lighting system **4** includes a switch **44** and a bias circuit **46**. In the embodiment, the switch **44** is an N-type metal-oxide-semiconductor field-effect transistor (NMOSFET) **N1**, coupled to the PWM circuit **12**, for selectively conducting or cutting off a connection between the microcontroller **10** and a ground **GND** according to the voltage of the current setup signal $Iset$, so as to convert the current setup signal $Iset$ from voltage to current. The bias circuit **46** includes resistors **R1**, **R2**, coupled between a power **VDD** and the ground **GND**, wherein a node **Nset** between the resistors **R1** and **R2** is connected to the microcontroller **10**, for providing a startup voltage **Vs** to the microcontroller **10**. As such, the lighting system **4** of the present invention may control the switch **44** according to the voltage of the current setup signal $Iset$ generated by the PWM circuit **12**, and further adjust the current I_{11} generated by the microcontroller **10** to the light emitting diode LED.

Furthermore, a drain, a source and a gate of the NMOSFET **N1** are respectively coupled to the microcontroller **10**, the ground **GND** and the PWM circuit **12**. When the voltage of the current setup signal $Iset$ is at the high voltage level, the NMOSFET **N1** may conduct a connection between the drain and the source. When the voltage of the current setup signal $Iset$ is at the low voltage level, the NMOSFET **N1** may cut off the connection between the drain and the source. Moreover, when the voltage of the current setup signal $Iset$ is at the low voltage level and the NMOSFET **N1** is cutoff, the current and the voltage at the node **Nset** is floating and electrically undefined. Accordingly, the current I_{11} generated by the microcontroller **10** to the light emitting diode LED is unstable and uncontrollable, which results in abnormal flickers of the light emitting diode LED.

Therefore, the lighting system **4** of the present invention utilizes the bias circuit **46** for providing the startup voltage **Vs** to the microcontroller **10**. Under such a circumstance, no matter the NMOSFET **N1** is conducted or cutoff, the current received by the microcontroller **10** is always stable, thus preventing abnormal flickers of the light emitting diode LED. In detail, the bias circuit **46** includes the resistors **R1**, **R2**, serially connected between the power **VDD** and the ground **GND**, wherein resistances of the resistors **R1**, **R2**

5

may be preferably selected, allowing a static current delivered from the power VDD to the ground GND to be low, so as to reduce a power consumption of the lighting system 4. In addition, a resistance ratio of the resistors R1, R2 may be adjusted, such that the startup voltage Vs may be biased at a highest voltage level where the microcontroller 10 is able to receive. As such, when the NMOSFET N1 is cutoff, the current received by the microcontroller 10 at the node Nset may approximate zero, which further reduces the power consumption of the lighting system 4.

Notably, the embodiments stated in the above are utilized for illustrating the concept of the present invention. Those skilled in the art may make modifications and alterations accordingly, and not limited herein. According to different applications and design concepts, the pulse width modulation circuit of the present invention may be altered. For example, under a circumstance that the microcontroller may adjust the current delivered to the light emitting diode by two levels according to the current received at the current setup pin, the current level generated by the pulse width modulation circuit of the present invention may be adjusted. The current setup signal in different current levels may be generated according to the two-level current scales which the microcontroller may identify, further increasing the lighting precision of the light emitting diode, which are also within the scope of the present invention.

The conventional control device may only turn the light emitting diode on or off, or adjust the brightness of the light emitting diode by two levels through the operations of the microcontroller. In comparison, the present invention utilizes the pulse width modulation circuit for providing the current setup signal to the microcontroller to adjust the brightness of the light emitting diode, allowing the control device to instantly and dynamically adjust the brightness of the light emitting diode LED. As such, the control device of the present invention may improve the lighting precision of the light emitting diode, for instantly and dynamically adjust the brightness of the light emitting diode. In addition, the present invention further utilizes the bias circuit for preventing the light emitting diode from abnormal flickers, which extends functionalities of the microcontroller to control the light emitting diode, elevates product quality and meets the user requirements.

Those skilled in the art will readily observe that numerous modifications and alterations of the device and method may be made while retaining the teachings of the invention. Accordingly, the above disclosure should be construed as limited only by the metes and bounds of the appended claims.

What is claimed is:

1. A control device, for a light emitting diode (LED), wherein the LED is driven by a current to emit light, the control device comprising:

a microcontroller, coupled to the LED, for providing the current to the LED according to a current setup signal; a pulse width modulation (PWM) circuit, coupled to the microcontroller, for generating the current setup signal, and adjusting a pulse width of the current setup signal according to a control signal, to adjust the current generated by the microcontroller; and a bias circuit, coupled to the microcontroller, for providing a startup voltage to a current setup pin.

2. The control device of claim 1, wherein the PWM circuit adjusts an average current value of the current setup signal according to the control signal.

6

3. The control device of claim 1, further comprising: a switch, coupled to the microcontroller, the PWM circuit and a ground, for conducting or cutting off a connection between the microcontroller and the ground according to the current setup signal, so as to allow the microcontroller to provide the current to the LED according to the current setup signal.

4. The control device of claim 3, wherein the switch is an n-type metal oxide silicon transistor (NMOS), and a drain, a source and a gate of the NMOS are respectively coupled to the microcontroller, the ground and the PWM circuit.

5. A control method, for controlling a microcontroller to control a light emitting diode (LED), the control method comprising:

adjusting a pulse width of a current setup signal delivered to the microcontroller according to a control signal; providing, by the microcontroller, a current to the LED and adjusting a value of the current according to the current setup signal, to adjust a brightness of the LED; and

providing a startup voltage to the microcontroller.

6. The control method of claim 5, wherein the step of providing, by the microcontroller, the current to the LED and adjusting the value of the current according to the current setup signal, so as to adjust a brightness of the LED is conducting or cutting off a connection between the microcontroller and a ground according to the current setup signal, to allow the microcontroller to provide the current to the LED according to the current setup signal.

7. The control method of claim 5, wherein the step of adjusting the pulse width of the current setup signal delivered to the microcontroller according to the control signal is adjusting an average current value of the current setup signal according to the control signal.

8. A lighting system, comprising:

a light emitting diode (LED), driven by a current to emit light; and

a control device, comprising:

a microcontroller, coupled to the LED, for providing the current to the LED according to a current setup signal;

a pulse width modulation (PWM) circuit, coupled to the microcontroller, for generating the current setup signal, and adjusting a pulse width of the current setup signal according to a control signal, to adjust the current generated by the microcontroller; and

a bias circuit, coupled to the microcontroller, for providing a startup voltage to a current setup pin.

9. The lighting system of claim 8, wherein the control device further comprises:

a switch, coupled to the microcontroller, the PWM circuit and a ground, for conducting or cutting off a connection between the microcontroller and the ground according to the current setup signal, so as to allow the microcontroller to provide the current to the LED according to the current setup signal.

10. The lighting system of claim 9, wherein the switch is an n-type metal oxide silicon transistor (NMOS), and a drain, a source and a gate of the NMOS are respectively coupled to the microcontroller, the ground and the PWM circuit.

11. The lighting system of claim 8, wherein the PWM circuit adjusts an average current value of the current setup signal according to the control signal.
